ELECTRIC MOTOR

Thomas W. Cole, Lima, Frayne L. Combs, Jr., Wapakoneta, and Benjamin F. Richer, Jr., and Langdon C. Schaefer, Lima, Ohio, assignors to Westinghouse Electric Corporation, a corporation of Pennsylvania

Application June 4, 1954, Serial No. 30,821

Term of patent 14 years

(Cl. D26—5)

Fig. 1.

Fig. 2.

To all whom it may concern:

Be it known that we, Thomas W. Cole, Frayne L. Combs, Jr., Benjamin F. Richer, Jr. and Langdon C. Schaefer, citizens of the United States, residing at Lima, in the county of Allen and State of Ohio; at Wapakoneta, in the county of Auglaize and State of Ohio; at Lima, in the county of Allen and State of Ohio; and at Lima, in the county of Allen and State of Ohio, respectively, have invented a new, original, and ornamental Design for an Electric Motor, of which the following is a specification, reference being had to the accompanying drawing, forming a part thereof, in which:

Figure 1 is a perspective view of one side of an electric motor showing the new design; and

Fig. 2 is a similar view of the opposite side of the motor.

The dominant portions of the design are shown in solid lines.

We claim:

The ornamental design for an electric motor, as shown and described.
